BY-PASS VALVE FOR HYDRAULIC DOOR-OPERATING SYSTEMS.

1,147,542.

Specification of Letters Patent.

Patented July 20, 1915.

Application filed June 26, 1914. Serial No. 847,469.

To all whom it may concern:

Be it known that we, FREDERIC JOHN PIKE and HERBERT NEVILLE, subjects of the King of Great Britain, and residing, respectively, 5 at 75 Cedars road, Beckenham, in the county of Kent, England, and 31 Elsinore road, Forest Hill, in the county of Kent, England, have invented new and useful Improvements in By-Pass Valves for Hydraulic Door-Operating Systems and the 10 like, of which the following is a specification.

This invention relates to improvements in valves for hydraulic systems especially 15 such systems as are applicable for operating bulkhead doors and the like, and more particularly it relates to an improved means for automatically putting the ram of the cylinder or cylinders operating each door in 20 equilibrium upon the cessation of pressure in the mains so that the door may be capable of free manual operation.

According to this invention a separate by-passing device is provided in a duct communicating with both ends of the cylinder or with both of the cylinders of a door, which device comprises firstly a valve arrangement of such a nature that, when pressure is admitted to either end of the cylinder or to either cylinder, the said valve arrangement automatically cuts off communication with the other end or other cylinder, and secondly, a device normally restrained from action by the said pressure which device on the failure of pressure is adapted 30 to actuate the valve arrangement for placing the two ends of the cylinder, or the two cylinders, in direct communication or short-circuit.

40 In order that the invention may be readily understood reference is made to the accompanying drawings, in which:

Figure 1 shows one form of by-passing device, and Figs. 2, 3 and 4 show modified forms.

In Fig. 1, a casing *a* incloses a chamber *b* having two openings *c* and *c'* which communicate with respective ends of the cylinder in a system employing a double acting cylinder, or with respective cylinders in a system employing two single acting cylinders operating on each door. Within the chamber *b* is placed a cylindrical valve *d* having valve faces *e* for closing on seatings 50 *f*. Winged extensions *g* slide within the openings *c* and *c'* and support the valve. In order that the valve may be induced to occupy a midway position upon the failure of pressure in the system, there is provided a plunger *h* at right angles to the axis of the valve *d*. The plunger *h* has a conical end *i* which projects into a suitable opening *j* in the valve *d*. When no hydraulic pressure exists the plunger *h* is pressed into the position seen in Fig. 1 by means of a spiral or other spring *k* and holds the valve in the mid position. The spring *k* is in a chamber *l* attached to the casing *a* and the plunger *h* is preferably provided with a stuffing box *m*. When one of the openings 15 for example *c*, of the valve chamber is placed in communication with the pressure fluid, the plunger *h* will be pressed up and the valve *d* will then be free to move over under the influence of the pressure to close 20 the opposite opening *c'*. When the pressure in the system ceases, the plunger *h* will be forced inward by its spring *k* and the extension *i* thereon will thereupon engage with the aperture *j* in the valve *d* and draw 25 the valve *d* into its mid position thereby putting both ends of the cylinder or both cylinders in communication and allowing 30 the door connected thereto to be freely manually operated.

Fig. 2 shows a modified construction. The casing *a* incloses two adjacent chambers *n* and *o* in communication one with each end of the cylinder or with each cylinder through passages *p* and *q*. The chambers *n* and *o* are connected by a passage *r* opening into the respective chambers through openings *s*. In each opening *s* is a valve *t* which closes the opening *s* when depressed, but which is constantly pressed away from its seat by a spring *u*. When no pressure exists both valves are forced off their seats by the springs and a free passage of fluid is permitted between the two chambers *n* *o*. The extremities of the valve stems are 40 formed at *v* as hollow rams working in chambers *w* and packed with cup leathers *x*, the springs *u* being inserted into the rams. In this construction when pressure fluid is admitted to either end of the cylinder or either cylinder of a door and consequently also to the corresponding chamber *n* or *o*, the valve in that chamber will be depressed.

so long as the pressure is maintained. Communication is thus cut off between the two ends of the cylinder or between the two cylinders of a door. Upon the cessation of pressure, both valves t rise under the influence of their springs and allow of the free passage of fluid from one end of the cylinder to the other, or from one cylinder to the other.

- 10 Another construction is illustrated in Fig. 3, in this arrangement, p and q are the two passages leading from each end of the cylinder or each cylinder, the passage p terminating in a chamber n and the passage q terminating in a chamber o . The chambers n and o may be put into communication through an opening s which is closed by a valve t . The valve is held away from its seat, when no pressure exists, by a spring u inclosed in an enlargement v of the valve spindle. The exposed annular area of the part v is made larger than the exposed annular area of that portion of the valve projecting beyond the seat and into the opening s , the ratio of such areas being suitably about two to one. The passages y and z leading from the chambers n and o communicate with the door controlling valve, the by-passing valve in this case being in 20 the pipes leading from the top and bottom of the cylinder or from each cylinder to the control valve. The valve device could be situated in a separate pipe communicating with the top and bottom of the cylinder or 25 with each cylinder, and in this case the passages y and z would be omitted. When pressure is admitted through the passage y to the passage p the valve t will be forced down and prevent communication between 30 the chambers n and o . When pressure is admitted through the passage z to the passage q , the valve t will be still held down by reason of the preponderance of the effective area of the exposed portion of the 35 valve stem extension v over the effective area of the exposed portion of the valve t in the opening s . The passages y and z may be restricted in diameter so that the speed of operation of the door may be decreased 40 as desired while the by-passing ports p and q may be left as large as convenient to allow of minimum fluid resistance when working the door manually.
- 45 A still further modification is illustrated in Fig. 4. In this construction two valves t and t' are provided and pressure fluid admitted at either q or p closes the valve t in the opening s or the valve t' in the opening s' , against a spring u which tends to force both valves outward. When 50 the fluid pressure ceases, the spring u will cause both valves t and t' to leave their seats, a free passage for fluid being thus afforded.
- 55 An important advantage is obtained with

this improved by-passing device, namely, that the fluid is allowed a short circuit passage which may be equal to or larger than the full bore of the pipe connections of the hydraulic cylinder, so that with a passage 70 of suitable size there is practically no hydraulic resistance whatever to the movement of the ram when the door or device is manually operated, and further that if any doors are disconnected from the system by closing 75 certain stop valves provided in connection with each door, free manual operation of such doors is at once possible while the free hydraulic working of the other doors of the system remains unaffected. 80

We claim:

1. A by-pass mechanism for fluid pressure operated bulkhead doors and the like, comprising a casing having means for connecting it with the fluid pressure mechanism of a door and having a passage adapted to afford a by-pass communication for said fluid pressure mechanism, an automatic valve in the passage adapted to close the latter under the influence of pressure fluid 90 when present in said casing, and means constantly influencing said valve and adapted to be overcome or restrained by such pressure fluid but operative upon said valve to open said passage and create a by-pass when relieved of the pressure of said fluid. 95

2. A by-pass mechanism for fluid pressure operated bulkhead doors and the like, comprising a casing having means for connecting it with the fluid pressure mechanism of a door and having a passage adapted to afford a by-pass for said fluid pressure mechanism, a valve in said casing, means constantly operative upon said valve in the direction for opening it, said valve being adapted to be operated by fluid pressure to close the passage through said casing to pressure fluid flowing in either direction and being operated by said means to open such passage when said fluid is no longer under pressure. 100

3. A by-pass device for hydraulically operated bulkhead doors and like systems, comprising a valve casing having two ports adapted to be connected with respective parts of the hydraulic operating mechanism, whereby either port may be connected with pressure while the other port is connected with exhaust when such mechanism is energized, a valve in said casing adapted to close either port under the influence of pressure admitted by the opposite port, and mechanism operative upon such valve to establish communication between the two ports when no hydraulic pressure is available. 115

4. A by-pass device for hydraulically operated bulkhead doors and like systems, comprising a valve casing having ports adapted to be connected with respective parts of the hydraulic operating mechanism whereby 120

- either port admits pressure fluid while the other conducts exhaust when such mechanism is energized, a valve and plunger device in a passage in said casing, said valve being adapted to close said passage under the influence of any pressure fluid admitted to said casing, and mechanical valve-operating means adapted to open said valve device when no fluid pressure is available.
- 5 10 5. A by-pass valve mechanism for fluid pressure operated bulkhead doors and the like, comprising a casing, a valve in said casing, valve opening means constantly operative upon said valve, a ram in said casing operative to restrain said valve opening means, and said valve adapted to close under the influence of pressure fluid present in said casing.
- 15 20 6. A by-pass device for hydraulically operated bulkhead doors and like systems, comprising a valve casing having two ports adapted to be connected with respective parts of the hydraulic operating mechanism whereby either port may be connected with pressure while the other port is connected with exhaust when such mechanism is energized, a valve in said casing adapted to close under the influence of pressure ad-

mitted by either port, and a spring operated device normally restrained from action by the hydraulic pressure but operative, when no pressure is available, upon the valve to move it to a position to open communication between the two ports.

7. A by-pass device for hydraulically operated bulkhead doors and like systems, comprising a valve casing having two communicating chambers each having a port, a valve situated in a port in the partition between the two chambers, the head portion 35 of the valve being situated in one chamber and an enlarged stem portion being situated in the other chamber and acting as a ram therein, the head and stem portions being so proportioned that the valve will close the 40 port in the partition between the chambers irrespective of the chamber to which pressure is admitted, and a spring device operative upon such valve to raise it from its seat upon the cessation of fluid pressure.

FREDERIC JOHN PIKE.
HERBERT NEVILLE.
